UNITED STATES PATENT OFFICE.

HENRY SHAPAN, OF BROOKLYN, NEW YORK.

COMMUTATOR-TRUING DEVICE.

Application filed June 4, 1927. Serial No. 196,462.

The present invention relates to a device for truing commutators and has for its principal object to provide a simple and efficient device which may be readily and easily assembled for use and which will furthermore be adapted for disposition on the armature shaft after the front bearing has been removed thereby permitting the commutator to be operated upon without requiring the removal of the commutator from the motor.

One of the important objects of the present invention is to provide a commutator truing device of the above mentioned character wherein the same includes a head stock which is adapted for rotation on the armature shaft, a tool carriage being arranged on the head stock for slideable movement thereon, means being provided for seating the tool carriage whereby the cutter will be moved along the commutator, additional means being provided for automatically operating the feeding mechanism during the rotation of the head stock about the armature shaft.

A still further object is to provide a commutator truing device of the above mentioned character which is simple in construction, inexpensive, and furthermore adapted to the purposes for which the same is designed.

Other objects and advantages of this invention will become apparent during the course of the following description.

In the accompanying drawings forming part of this specification and in which like numerals are employed to designate like parts throughout the same:

Figure 1 is a side elevation of the commutator truing device embodying my invention showing the same in use.

Figure 2 is an end elevation thereof.

Figure 3 is a top plan view of the device, parts thereof being broken away.

Figure 4 is a vertical sectional view taken substantially on the line 4-4 of Figure 2 looking in the direction of the arrow.

Figure 5 is a similar section taken on the line 5-5 of Figure 1 looking in the direction of the arrows.

Figure 6 is a top plan view of the top section of the sectional head stock.

Figure 7 is a sectional view taken substantially on the line 7-7 of Figure 1 looking in the direction of the arrows.

Figure 8 is a fragmentary detail perspective view of the forward end portion of the tool carriage.

Figure 9 is a detail perspective view of the

worm shaft forming a part of the carriage seating means.

Figure 10 is a detail of the pawl showing the ratchet wheel associated therewith. 60

Figure 11 is a detail perspective view of a shim.

In the drawings wherein for the purpose of illustration is shown the preferred embodiment of my invention, the numeral 1 designates generally the head stock, the same comprising a complementary top and bottom section 2 and 3 respectively. The top section is preferably in the form of a block and is formed with a substantially V-shaped cut-out portion in the bottom thereof, while the bottom section 3 is in the form of a substantially V-shaped plate member.

Laterally extending flanges 4 are formed on the bottom of the top section 2 while similar flanges 5 extend outwardly from the top of the bottom section 3 at the side thereof and these complementary flanges are provided with registering openings to accommodate the securing bolts 6 whereby the top and bottom sections of the head stock may be clamped around the armature shaft A after the front bearing thereof has been removed. The sections of the head stock are not clamped on the armature shaft so that the head stock is not free to move and this head stock is adapted for rotation about the armature shaft in a manner to be hereinafter more fully described.

The top section 2 of the head stock 1 is formed with the angularly disposed threaded sockets 7 into which are threaded the inner threaded ends of suitable elongated handles 8 and similar threaded sockets are formed in the bottom section 3 for accommodating the inner threaded ends of additional handles and in this manner, the handles 8 will extend radially from the head stock 1, in the manner as clearly illustrated in Figure 5. These handles provide means whereby the head stock may be manually rotated about the armature shaft.

The block comprising the top section 2 of the head stock 1 is formed in its upper face with the longitudinally extending handle or slot 9 which provides a guide means for accommodating the longitudinally movable tool carriage the construction of which will now be specifically described.

This tool carriage comprises an elongated bar 10 which is of such cross sectional shape as to cooperate with the longitudinal guide channel or slot 9 formed in the top of the

block comprising the upper section of the head stock 1 which is clearly illustrated in Figures 2 and 5 of the drawings. The forward end of the bar 10 is slotted as indicated at 11 with reference more particularly to Figure 8 and secured within this slot is the cutting tool 12, the same being supported in proper position in the slot by means of the transversely extending screw or bolt 13 which is threaded through a suitable opening 14 provided therefor in one of the fur- cations formed by the slot 11.

The bottom face of this bar 10 comprising the traveling carriage is formed with trans- versely curved cut-out portion and this portion of the bar is formed with the thread or rather teeth 15 in the manner as clearly il- lustrated in Figures 4 and 7 of the drawings. The purpose of the teeth 15 formed in the 20 bottom face of the bar 10 will also be present- ily described.

The block comprising the top section 2 is provided with a channel 16 which extends in- wardly from the rear end of the block and is 25 formed in the bottom of the channel 9 to ac- commodate the forward end of the worm shaft 17. The forward end portion of the worm shaft is circular in cross section while the outer end portion which extends beyond 30 the rear end of the block is of hexagonal shape as indicated at 18 with reference more particularly to Figure 9 of the drawings. The block is further formed with the cut-out portion 19 in the bottom of the channel 9 and 35 this cut-out portion 19 intersects the cut-out portion 16 as clearly illustrated in Figure 6 of the drawings.

The circular inner end portion of the worm shaft 17 carries thereon the worm gear 20 and 40 the same is adapted for disposition within the cut-out portion 19 in the manner as clearly shown in Figure 4. This worm is integrally associated with the shaft 17 whereby the same rotates simultaneously with the shaft and the 45 worm is adapted for cooperation with the teeth 15 formed in the bottom face of the bar 10 in the manner as clearly shown in Figure 4.

The worm 20 cooperates with the teeth 15 50 to provide a feeding means for moving the bar 10 forwardly whereby the cutter 12 will be fed along the outer peripheral face of the commutator B which is to be trued and for the purpose of automatically operating the 55 feeding mechanism there is provided a pawl and ratchet structure the details of which will now be fully described.

An enlarged toothed member 21 is disposed 60 over the outer end portion of the armature shaft A and for the purpose of securing this toothed member rigidly on the shaft there is provided an annular collar or flange 22 on the inner face of this toothed member and suitable set screws or the like 23 extend through 65 the flange or collar and engage the armature

shaft in the manner as is very clearly illus- trated in Figure 4 of the drawing. The toothed member 21 is adapted for disposition adjacent the rear end of the rotatable head stock 1.

Cooperating with the toothed member 21 is the pawl designated generally by the nu- 70 meral 24 which is operatively associated with the hexagonal outer end portion 19 of the worm shaft 17. This pawl comprises a pair of 75 similar plates each of which has its sides gradually converging toward the lower end and the smaller lower end portions of these plates are disposed in abutting relation while the larger upper end portions thereof are dis- 80 posed in parallel spaced relation in the man- ner as clearly shown in Figures 1 and 4 of the drawings. Each plate is designated by the numeral 25. The upper enlarged por- 85 tion of each plate is formed with a substan- tially hexagonal opening and the openings are arranged in alinement with each other to accommodate the hexagonal outer end por- 90 tion 18 of the worm shaft 17. The purpose of spacing the upper larger portions of the plates is to provide a means to accommodate the relatively small ratchet wheel 26 and this ratchet wheel is also formed with a hexagonal opening 27 to accommodate the hexagonal outer end portion 18 of the worm shaft 17. 95 A pivoted dog 28 is arranged between the plates for cooperation with the teeth of the ratchet wheel 26 to prevent rotation of the same in one direction as is clearly illustrated in Figure 10.

A rod 29 has its inner end fitted in the rear end portion of the block comprising the top section 2 of the head stock 1 and this rod extends outwardly adjacent the inter- 100 mediate portion of the pawl 24. This rod provides a means for attaching the free ends of a spring member 30 which spring member has a portion thereof extending around the hexagonal portion 18 of the worm shaft 17 on opposite sides of the pawl 24. The in- 105 termediate portion of this spring member is bent downwardly for disposition against the rear side of the pawl 24 and this is clearly 110 illustrated in Figures 1, 2 and 4 of the draw- 115 ings. This spring member 30 normally urges the smaller end of the pawl into engagement with the teeth of the ratchet member 21. It is of course to be understood that the plates 25 comprising the pawl 24 are secured to- 120 gether so that the same will operate sim- ultaneously and furthermore due to the shape of the outer end of the worm shaft, said pawl will operate simultaneously therewith.

The operation of my improved commutator truing device may be briefly stated as follows: 125 When the parts are arranged as shown in Figure 1 of the drawings, it will be readily obvi- ous that when the handles 8 are moved in one direction, the head stock 1 will revolve about the armature shaft A and during such move- 130

ment, the pawl 24 being in engagement with the teeth of the ratchet member 21 will impart rotary movement to the worm shaft 17 and the worm 20 carried thereby will in turn cooperate with the teeth 15 of the bar 10 whereby to feed the carriage forwardly thus moving the cutter 12 forwardly along the peripheral face of the commutator and this will provide means whereby a step by step movement will be imparted to the feeding mechanism to insure the proper cutting of the commutator whereby the latter may be trued and all rough surfaces removed from the peripheral face thereof.

15 The simplicity of my commutator truing device will save considerable time and labor in the truing up of commutators and furthermore the parts are so arranged as to enable the device to be easily and accurately assembled or disassembled. Furthermore, whenever it becomes necessary to increase the height of the stock worm in order to accommodate commutators of different diameters, there may be provided for use with the stock 25 one or more shims such as are shown at 31 with reference more particularly to Figure 11 of the drawings. This shim is adapted for disposition between the armature shaft A and either of the sections of the head stock and is further maintained in proper position by means of the lateral flanges 32 formed on the side edges thereof and which flanges are provided with openings adapted for regis- 30

tration with the openings formed in the lateral flanges 4 and 5 to accommodate the securing bolt 6.

It will thus be seen from the foregoing description, that I have provided a commutator truing device which will at all times be positive and efficient for carrying out the purposes 40 for which it is designed.

While I have shown the preferred embodiment of my invention, it is to be understood that various changes in the size, shape and arrangement of parts may be resorted to without departing from the spirit or sacrificing 45 any of the advantages of the appended claim.

What I claim is:

In a commutator truing device comprising a head stock adapted for rotation on the armature shaft, the upper portion of the head stock being bifurcated in longitudinal respect to the armature shaft, to provide a pair of up-standing spaced furcations, the opposed faces of the furcations being formed with grooves, 50 an elongated tool carrier, said carrier provided with a longitudinally extending rib, at opposite sides thereof for sliding engagement within said grooves, a rack provided at the bottom of the carrier, a worm mounted for 55 rotation between the furcations and in mesh with said rack, and means connecting the armature shaft with the worm for rotating the latter.

In testimony whereof I affix my signature.
HENRY SHAPAN.
